Primary Examiner — Sandra Snapp

CLAIM

(57) The ornamental design for a dispenser housing, as shown and described.

DESCRIPTION

FIG. 1 is an isometric view of a top, front, and left side of an ornamental design for a dispenser housing;

FIG. 2 is a front elevational view of the dispenser housing of FIG. 1, all other sides being identical thereto;

FIG. 3 is a top plan view of the dispenser housing of FIG. 1; and,

FIG. 4 is a bottom plan view of the dispenser housing of FIG. 1.

The broken lines are for the purpose of illustrating environmental structure and form no part of the claimed design.
